CLAIM

The ornamental design for a shoe as shown and described.

DESCRIPTION

FIG. 1 is a front bottom perspective view of a shoe showing our new design;

FIG. 2 is a bottom view thereof;

FIG. 3 is a rear bottom perspective view thereof; and,

FIG. 4 is an enlarged view of the claim as shown in FIG. 2 with environment removed for clarity purposes.

The broken line immediately adjacent to and surrounding the photographic area defines the peripheral bounds of the claimed design and forms no part thereof. The broken lines depicting the remainder of the shoe form no part of the claimed design.
